WELL PUMP

Dee E. Humphrey, Dallas, Tex.

Application August 8, 1940, Serial No. 351,839

5 Claims. (Cl. 103—158)

This invention relates to well pumps and more particularly to pumps for deep oil and artesian wells.

The principal object of the invention is to dispense with heavy and expensive equipment usually employed for pumping wells, including sucker rods, surface equipment such as pumping units, jacks and powers and replace such equipment with a simple, inexpensive and durable reciprocating element, suspended on the tubing string at the bottom of the hole.

Another object of the invention is to provide means for rotating the tubing string as well as means for translating such movement into reciprocating movement for so actuating the working barrel, thereby to elevate liquid through the tubing in successive stages, aided by a series of relatively spaced and conventional valves.

Another object of the invention is to provide means by which any differential speed ratio may be obtained between the rotatable speed of the tubing and the reciprocable speed of the working barrel. For example, rotation of the tubing at the rate of 60 R. P. M. will cause the working barrel to travel approximately 200 inches in effective work and which ratio may be changed by varying several factors in the assembly.

The invention has further advantages in that it produces a continuous swabbing effect on the well; minimizes accumulation of basic sediment, paraffin deposits, emulsion, sand and the like at the bottom of the hole, due to the agitation set up at this point by the action of the working barrel.

With the foregoing and other objects in view, the invention has particular reference to certain salient features of construction and arrangement of parts to become manifest as the description proceeds, taken in connection with the accompanying drawings, wherein:

Figure 1 is a view of the invention in vertical section showing one form of power transmission in the well and the means for converting rotary into reciprocating movement for actuating the working barrel.

Figure 2 is a continuation of Figure 1.

Figure 3 is an expanded view of the lowest section of tubing, showing double helix grooves in its exterior surface.

Figure 4 is a transverse section, taken on line 4—4 on Figure 1.

Figure 5 is another form of the invention from which the power transmission in the well has been deleted, resulting in a fixed speed ratio between the tubing and working barrel.

Figure 6 is a continuation of Figure 5.

Figure 7 is a transverse section, reduced, on line 7—7 on Figure 5.

Figure 8 is a transverse section, reduced, on line 8—8 on Figure 5, and

Figure 9 is a reduced transverse section on line 9—9 on Figure 5.

Continuing with a more detailed description of the drawings, the reference numeral 1 denotes a well casing, on which is suitably mounted a driving head 2, for rotating a string of upset tubing 3, suspended within the casing 1.

The driving head 2 is shown in the drawings to contain a conventional worm and gear assembly for transmitting rotary movement to the tubing string but in actual practice, a speed reduction mechanism, as set forth in applicant's U. S. Letters Patent No. 2,206,958, issued July 9, 1940, will provide an effective drive for this purpose as well as affording a medium, not unlike that illustrated in Figure 1, for transmitting power to and reducing the speed of the lowermost section 4 of tubing in the string and which section will be described presently.

The gearing in the head 2 as shown consists of a worm gear 5, mounted on bearings 6, upon a boss 7. The squared end 8 of the upper section of tubing extends through a central opening in gear 5 and through a square opening in a block 9, which latter, in turn, rests in a square recess in the gear 5. This arrangement enables gear 5 to rotate the tubing string 3. To drive the gear 5, a worm 10 is mounted on shaft 11 to mesh with the teeth of gear 5 and a V-belt pulley 12 is mounted also on shaft 11 and operated by a motor to rotate shaft 11. Suitable packing 13 surrounds the tubing 3 in the head 2 and is held in place by means of a thrust collar 14.

Suspended by the tubing string 3 is a housing 15. This housing is provided with an internal shoulder or ledge 16 which serves as a lower race for ball bearings 17.

A member 18 has an internally geared flange 19 and is fixed, by means of keys 20, to the tubing 3 to rotate therewith. The teeth of the gear of flange 19 enmesh a segment of the teeth of external gear 21, the gears being eccentrically related, as set forth in the above identified patent. Both gears rest upon the bearings 17.

It is to be noted that the lowermost tubing section 4 is joined to and depends from external gear 21 and consequently rotates at whatever speed the gear 21 is designed to rotate, which is usually at a faster rate than that of the tubing 3.

The housing 15 is held against rotation by

means of grips 22 and from this housing depends a tubular guide 23 in which operates the working barrel 24. Shoes 25 are fixed to the walls of the working barrel 24 (Figure 2) and being channel shaped, embrace vertical ribs 26, affixed to the interior wall of the tubular guide 23. In this manner, the working barrel 24 is constrained to reciprocate in strict concentric relationship with the tubular guide 23. Moreover, the working barrel is held against other than reciprocating movement by these shoes and guide ribs 25.

The mechanism by which rotation of the tubing string is converted into reciprocation of the working barrel is based upon the well known mechanical movement involving a rod having a pair of helical grooves, intercrossing throughout the length of the rod and merging at their ends to form an endless reversing groove for a conforming protuberance carried by another member embracing the rod. In the present usage, however, the rod takes the form of the hollow tubing section 4, in the exterior wall surface of which is provided the continuous groove 27. Figure 3 shows the form of the groove when spread out on a flat plane, and in which it is to be noted that the original pair of grooves are merged at *a* at the top and bottom in order that the template or protuberance 28, integral with the cylindrical body (Figure 4) may travel in the groove from one end of the tubing section 4 to the other and will be enabled to reverse its direction of travel at each point *a*. The protuberance 28 is the sole supporting means for the working barrel 24 and suspends this member from the grooved section 4.

In the bottom of the working barrel 24, a ball valve 29 is provided and on the lower extremity of the working barrel, a strainer 30 may be provided, if desired.

A similar valve 31 is mounted in the bottom of the grooved tubing section 4 and immediately below the valve 31, piston type rings 32 are provided on the section 4 to engage the interior surface of the wall of the working barrel 24.

It is pointed out that while there is shown a concentric space between the working barrel and the tubing section 4, it is intended that these elements be in contact one with the other but allowing easy sliding movement of the working barrel without too great friction.

In operation, the tubing string 3, carrying the housing 15 and grooved section 4 is run into the casing much in the same manner as is usually done. When power is applied to the pulley 12, worm 10 will rotate gear 5 to revolve the tubing string 3. This will impart rotation to the internal gear 18 and which, in turn, will revolve the gear 21 to rotate the tubing section 4. Obviously, rotation of section 4 will cause the protuberance 28 to move up or down, depending upon the angle of the groove in which it is disposed and in moving down, the working barrel 24 is lowered so that it will be submerged in the liquid 31 in the bottom of the well. Fluid will enter the working barrel by lifting ball 29 and when the protuberance 28 has reached the lower limit of the groove 27 at *a*, its direction of travel will be reversed and the working barrel 24 will begin to ascend, carrying with it the fluid. As the working barrel continues to rise, the fluid therein will lift the ball 31 in the bottom of the section 4, thereby entrapping the same above the valve. As the operation continues, the fluid load will be assumed by the tubing valve 32,

shown in Figure 1 at the lower end of the tubing string 3.

It is apparent from the foregoing that any speed differential desired between the tubing and working barrel may be effected by changing the gears 18 and 21 or substituting for the tubing section 4, other sections whose grooves have greater or lesser pitch.

In the form of the invention shown in Figures 5 to 9 inclusive, substantially the same principle is carried out and the structure varies from that just described chiefly in that the transmission gearing in the well is omitted. In place of the gearing there is provided a circular plate 33, welded or otherwise suitably secured to the upper end of a tubular guide 34. To this plate is pivoted grips 35, which, under pressure of springs 36 are urged against the walls of casing 37 to hold the tubular guide against rotation. The plate 33 and consequently the tubular guide is supported upon ball bearings 38, borne by a thick walled collar 39. This collar is threaded to receive the swaged end 40 of a tubular member 41, comparable to the tubing section 4 in the first described form of the invention.

The member 41 is provided with a helical endless groove 42 in which travels the protuberance 43, mounted in the upper end of the working barrel 44. This working barrel is guided and held against rotation in the tubular guide 34 by channel members 45 carried by the wall of the working barrel 44 and which embrace vertical ribs 46 mounted interiorly of the tubular guide 34.

A valve 47 is provided in the bottom of the working barrel 44 and a similar but smaller valve 48 is carried in the bottom of the tubular section 41.

The tubing string 49 from which the pumping elements described are suspended may be rotated by a mechanism similar to that earlier described and which consists of a gear 50 driven by a worm 51, which, in turn, is driven by a V-type belt pulley 52. A square block 53 is accommodated by a square recess in the gear 50 and a square hole in the block receives the con-forming end of the tubing string 49.

The operation of this form of the invention being substantially the same as that previously described, further description is deemed unnecessary. When the fluid, elevated by the working barrel reaches the top of the tubing string, it emerges into the driving head 54 and enters a discharge line 55 for transfer to storage.

Manifestly, the construction as shown and described is capable of some modification and such modification as may be constructed to fall within the scope and meaning of the appended claims is also considered to be within the spirit and intent of the invention.

What is claimed is:

1. A well pump including in combination with a tubing string in a well, surface means for rotating said tubing string, a tubular body suspended below said tubing string for common rotation therewith and having a continuous, double helix groove in its exterior surface, a working barrel surrounding said tubular body and held against rotation, having a member disposed in said groove to travel therein when said tubing string is rotated, whereby to effect vertical reciprocation of said working barrel, and valve means in said working barrel and said tubing string for

controlling fluid for upward passage through said tubing string.

2. A well pump including in combination with a tubing string in a well, surface means for rotating said tubing string, a working barrel, a multiple return grooved tubular member suspended by said tubing string and rotatable therewith in said working barrel, a tracer carried by said working barrel and disposed in said groove to effect extended rectilinear movement of said working barrel when said tubing string is rotated, and valve means carried by said working barrel and tubing string to elevate fluid from said well through the movements of said working barrel.

3. A well pump including a tubing string and means to rotate said tubing in a well, a multiple return grooved tubular member below and rotated by said tubing, a valve therein, a working barrel concentrically embracing said tubular member, a tubular guide concentrically embracing said working barrel and arranged to hold the same against rotation, tracer means carried by said working barrel arranged to travel in the groove of said tubular member to cause said working barrel to move rectilinearly in continuous motion when said tubing is rotated, to elevate fluid from said well.

4. A well pump including a tubing string, surface means for rotating said tubing string, a

speed reduction gearing suspended by said tubing in said well, a multiple return grooved tubular member suspended from said gearing and rotated thereby through the medium of said tubing, valves in said tubing, a working barrel surrounding said tubular member, a tracer carried by said working barrel arranged to travel in the groove of said tubular member and capable of reversal at either end of said tubular member for reciprocation of said working barrel, and valve means in said working barrel to effect transfer of well fluid above the valves in said tubing string.

5. A well pump including a tubing string and means for rotating the same in a well, valves in said tubing string, a working barrel below and suspended by said tubing string and held against other than extended rectilinear motion and return, a valve in the lower end thereof, an elongated hollow body suspended in said working barrel by and rotated through the medium of said tubing string, said body having multiple return grooves in its exterior surface, a valve therein, and means carried by said working barrel and disposed in said grooves to effect extended rectilinear motion of said working barrel when said tubing string is rotated, to elevate fluid from said well through said valves.
